CLAIM

The ornamental design for a stand for a device, as shown and described.

DESCRIPTION

FIG. 1 is a top perspective view of a stand for a device;

FIG. 2 is a front view thereof;

FIG. 3 is a back view thereof;

FIG. 4 is a left-side view thereof;

FIG. 5 is a right-side view thereof;

FIG. 6 is a top view thereof; and,

FIG. 7 is a bottom view thereof.

The portions of the stand for a device shown in broken lines form no part of the claimed design.

1 Claim, 7 Drawing Sheets
